UNITED STATES PATENT OFFICE.

CALEB E. TOWER, OF ROCKFORD, ILLINOIS, ASSIGNEE, BY MESNE ASSIGNMENTS, TO HOWARD D. COLMAN, LUTHER L. MILLER, AND HARVEY A. SEVERSON, COPARTNERS DOING BUSINESS AT ROCKFORD, ILLINOIS, AS BARBER-COLMAN COMPANY.

BOBBIN-CLEARER.

1,070,751.

Specification of Letters Patent. Patented Aug. 19, 1913.

Application filed May 15, 1908. Serial No. 432,961.

To all whom it may concern:

Be it known that I, CALEB E. TOWER, a citizen of the United States, residing at Rockford, in the county of Winnebago and State of Illinois, have invented certain new and useful Improvements in Bobbin-Clearers, of which the following is a specification.

This invention relates to mechanism for removing the waste yarn lint or thread from a core.

The form of mechanism herein shown is designed to remove waste yarn lint and threads from a bobbin and carry off the removed matter. The bobbins usually retain a portion of the lint and threads when they have become exhausted during the spooling process, or when they have been used in a loom. The usual method of removing the waste is by hand, either by grasping the shank of the bobbin and striking its nose against some unyielding object, or by cutting with a knife. Either of the above enumerated methods is undesirable for many reasons. The chief reason is that the bobbin is marred and thereby soon rendered unfit for use. By using a mechanism involving the generic features herein shown I am enabled to place the bobbins into a hopper or magazine from which they may be fed to a clearing mechanism and discharged to a proper receptacle and freed from all extraneous matter.

In the drawings, Figure 1 is a perspective view of the machine constructed in accordance with my invention. Fig. 2 is a side elevational view of the same. Fig. 3 is a plan view of the machine. Fig. 4 is a view, partly in section and partly in elevation, of the clearing mechanism. Fig. 5 is an enlarged sectional view through one of the supporting standards showing the feed for one of the bobbin clamps, the cutter bar being shown in elevation. Fig. 6 is a view of the cutter bar, one of the bobbin clamps and the actuating mechanism for the cutter bar and clamp, the supporting posts for the clamp and cutter bar and a portion of the feed wheel for the bobbins being shown in section. Fig. 7 is a detail view of a portion of a bobbin showing the posi-

tion of the pusher finger preparatory to pushing some of the yarn toward the cutter; and Fig. 8 is a similar view showing the yarn pushed away from the butt of the bobbin (within reach of the cutter). Fig. 9 is a detail view illustrating the relation of the pusher fingers to the bobbin.

The mechanism for selecting and feeding the bobbins, as well as a clearing mechanism, may be supported upon a base 1 having standards 2. On the base 1 are posts 3 and 4 (Fig. 3) having bearings 5 and 6, respectively, in which is journaled a drive shaft 7. The shaft 7 is provided with a pulley 8 loose thereon and a fixed pulley 9. Adjacent to the pulleys, is a belt shifter 10 operable by a crank arm 11 (Fig. 2) on the bracket 12, said crank arm receiving motion from the rock shaft 13 having a connection with said crank arm 11 through the medium of the link 14 to which is connected, at one end, a contraction spring 15, by a pin 16; the other end of the spring being connected to the underside of the base 1. The rock shaft may be rocked in its bearings 17 and 18 on the standards 2 through the medium of a pedal 19 rigid with said rock shaft. The actuation of the rock shaft will cause movement to be imparted to the belt shifter 10 so as to shift the belt from the loose pulley to the drive pulley. When pressure is relieved from the pedal 19, the belt will be shifted back to the loose pulley on account of contraction of the spring 15. Any suitable means may be employed in lieu of the pedal mechanism for causing a continuous operation of the machine. On the end of the shaft 7 opposite that to which the pulleys are secured, is a pinion 20. The pinion 20 is in mesh with the gear 21 on a shaft 22 in the bearing 23 on the post 24.

25 is a pinion on the shaft 22 and in mesh with a gear 26 loose on a shaft 27 in bearings on the posts 28 and 29. The gear 26 may be frictionally held to the shaft 27 by turning the hand disk 30 having a sleeve 31. When the disk 30 is turned, it will cause the adjacent faces of the gear 26 and the disk 32 to come together to frictionally engage each other, the disk 32 being rigid with the shaft 27 so as to turn therewith. The clutch fea-

ture may be omitted if desired and the shaft 27 may be positively driven through the gearing from the shaft 7. The shaft 27 drives certain operating mechanism for feeding the thread container elements, to be hereinafter referred to as bobbins, to the positioner and pusher devices. On said shaft 27 (see Figs. 2, 3, 4 and 6), are cams 33 and 34, the cam 34 actuating one of the bobbin 5 positioners or clamps and the cam 33 controlling the cutter bar which receives its rectilinear movement from a crank arm 35 on the end of said shaft 27.

I shall first describe how the bobbins are fed to clearing position.

By reference to Figs. 1 and 3 it will be observed that the bobbins may be received in a hopper or chute 36 supported on the frame of the machine. The discharge end 10 of said hopper terminates adjacent the positioning mechanism illustrated as two longitudinally moving clamps, one of which is positively actuated and the other yieldingly supported. The feed mechanism for the 15 bobbin comprises a shaft 37 in suitable bearings on the base 1 and running substantially the entire length thereof. The shaft 37 may be actuated by a Geneva stop motion which is driven (in the machine 20 shown) from the shaft 27 through the bevel gears 38 and 39 (Fig. 1), one of which is on the shaft 27 and the other on the shaft 40 in the bearing 41 on said base 1. The shaft 40 carries a crank arm 42 having an 25 anti-friction roller 43 on the end thereof, which is adapted to intermittently enter successive slots 44 in the star wheel 45 on the end of the shaft 37 (see Fig. 1) so as to give an intermittent movement to said 30 shaft 37. Between intermittent movements imparted through the crank arm 42 and its co-operating mechanism, the shaft 37 will be held against movement by a disk 46 fixed on the shaft 40 and adapted to engage the 35 notches 47 in the periphery of the disk 45. The contour of the notches corresponds to the arc of the periphery of the disk 46 so that said shaft 40 may rotate without imparting movement to the disk 45 unless the 40 roller on the arm 42 engages a slot 44. Alining with the discharge end of the hopper 36 and spaced a suitable distance apart are the feed wheels 48 and 49 carried on the shaft 37. These wheels or disks 48 and 49 45 are provided with peripheral notches 48^a and 49^a, respectively, the notches on the disk 49 being preferably smaller than those on the disk 48 because the disk 49 will engage the smaller end of the bobbin while the 50 disk 48 will engage the larger end. The notches 48^a and 49^a are preferably of shapes to conform to the contour of the ends of the bobbins so as to better engage them. It is apparent that the intermittent motion given 55 to the shaft 37 will impart a corresponding

motion to the disks 48 and 49 so as to intermittently feed the bobbins B to the clamping mechanism which positions the bobbins preparatory to the removal of the waste thread and lint therefrom.

The positioning mechanism may comprise a longitudinally movable clamp rod 50 (Fig. 6) supported in bearings in the posts 51 and 52. The rod 50 is provided with a collar 53 interposed between which and the post 51 is 70 an expansion spring 54 which tends to move the rod 50 into engagement with a bobbin brought by the disks 48 49 into alignment with said rod. The rod 50 is moved out of engagement with the bobbin and permitted to move into engagement therewith, by the cam 34 which acts upon an anti-friction roller carried by a lever 58, said lever being pivoted upon a shaft 55 mounted in 75 bearings 56. The lower end of the lever 58 is connected with one end of the rod 50 through the medium of a link 74. Hung from the shaft 55 is a lever 57 which is provided with an anti-friction roller 59 to bear against the periphery of the cam 33 on the shaft 27. Said lever 57 is connected to a rocking elbow lever 61 on the post 62 (see Fig. 6) by a link 63. The lever 61 is provided with an anti-friction roller 64 which bears against the nether side of the cutter bar so as to support it when it is raised. The lever 61 is also provided with a tooth or dog 65 to move into and out of engagement with a shoulder of the notch 66 in the rod 50. A contraction spring 67 connected 80 to the lever 57 at 68 and to the post 51 at 69 has a tendency to move the lever 57 against the action of its cam 33 so that said roller 59 on the lever 57 will, at all times, be 85 in position to be engaged by said cam. The end of the rod 50 is provided with a bobbin engaging socket comprising a flared portion 70 within which is a spring pressed ejector 71, the spring 72 of which is sufficient to cause the ejector 71 to prevent the bobbins 90 being stuck in the flared portion 70. The rod 50 is given a rectilinear movement through the medium of its rocking lever 58 and the cam 34 which actuates it. The 95 cutter bar is driven from the shaft 27 100 through the medium of the crank arm 35 (see Figs. 3, 4 and 6). The cutter bar 75 is provided with an elongated slot 76 the edges of which are adapted to engage the roller 77 on the post 51, whereby said 105 bar 75 may be supported at one end. The roller 64 also assists in temporarily supporting said bar preparatory to bringing the cutter into contact with the material to be removed from the bobbin. The crank 110 35 is connected to the bar 75 through a link 78. The forward end of the bar 75 is provided with an idler pulley 79 on a stud 80. In bearings secured on the bracket 82 carried by the bar 75 is a rotatory cutter 83, 115

said cutter having a shaft 84 on which is a pulley 85, whereby said rotatory cutter may be driven from a belt. The bracket 82 is rigidly fastened to the cutter bar 75 and is practically a part of it. Guard fingers 121 are adjustably secured to the cutter bar 75 by means of a pivot 121^a and screws 86 and 87, the screw 86 passing loosely through a finger 88 on the cutter bar and 10 having a screw-thread engagement with an arm 81^a rigid with said guard fingers. The screw 87 has a screw-thread engagement with the finger 88 and bears against the arm 81^a. These screws are for the purpose of 15 adjusting the guard fingers 121 with relation to the bobbins on which they slide.

That part of the bobbin-positioning mechanism which clamps the base or butt end of the bobbin comprises an ejector sleeve 117 (Figs. 4 and 5) on the rod 118 fixed in the recess 119 in the post 90. The rod 118 has a head or enlargement 118^a which engages the hollow portion of the butt end of the bobbin B. The other part of the positioning mechanism includes the reciprocating rod 50 with its ejector 71 and its spring 72. In the post 90 is a spring-pressed rack bar 91, the spring 92 surrounding the bar 91 and being held within the barrel 93. One end of 20 the spring 92 presses against the bushing 94 and the other end against a collar 95 on said bar. The teeth 96 of the rack 91 engage the pinion 97 on the shaft 98 in the post 90, the teeth of the pinion 97 being in engagement with the longitudinally movable and vertically rockable rack 99 having an elongated slot 100 engaged by a roller 101 in post 90, one end of said rack terminating 25 in the arm 102 to which is connected a pivoted guide rod 103 having one end passing through an opening 104 in an arm 105 carried by the post 90. Interposed between the arm 105 and the arm 102 is an expansion spring 106, the natural tendency of which is 30 to force the arm 102 upward and the opposite end of the rack downward. The opposite end of the rack 99 carries a pusher comprising a pair of pusher fingers 107 to engage the threads, yarn or other substance 35 at the base of the bobbins and force that part of it adjacent its uppermost point toward the nose of the bobbin (see Figs. 7 and 8) and into engagement with the rotatory knife or cutter 83. When in retracted 40 position, the pusher fingers are held elevated by the shoulder 107^a resting upon a block 107^b. The lateral projection 108 on the rack 99 is adapted to be engaged by the roller 89 as the cutter bar is lifted by the 45 roller 64 after the forward movement of said cutter bar is completed. (See Fig. 4).

By reference to Figs. 4 and 6 it will be observed that the post 52 carries a vertically movable spring-pressed block 109 50 which rests against the upper edge of the

bar 75 and places tension on said bar on account of the spring 110 interposed between the top of the recess in said post 52 and the upper edge of the block 109, thus holding the cutter upon the bobbin during the cutting stroke. On the driven shaft 7 is a band pulley 111 around which passes a belt or band 112, said band 112 engaging the periphery of the pulley 79 carried by the bracket on the cutter bar and pulley 85 on the shaft 84 on which the cutter disk is carried. This band also passes over a pulley 113 on a shaft 116 (Fig. 2) in the post 90. The pulleys 111 and 113 are on fixed axes, while the pulleys 79 and 85 are on constantly changing axes, the latter being due to the fact that the supports for the pulleys 74 and 85 will be constantly moving toward or away from the post 90. In order to take up slack from the band 112 the shaft 116 may be adjusted along the elongated slot 115 in said post 90 and held in its adjustment through the medium of the hand nut 114.

Motion is imparted to the drive shaft 90 either by the operator placing his foot upon the pedal 19 so as to shift the belt from the loose pulley to the drive pulley or through any other manner of starting the machine. Motion will be imparted to the shaft 27 95 through the pinion and gears 20, 21, 25 and 26 and said shaft 27 will cause the shaft 37 to receive movement through its Geneva stop motion. The rotation of the shaft 37 will cause the disks 48 and 49 to carry the 100 bobbins around to the positioning devices shown as comprising the rod 50 and the spring-pressed alining clamp including the sleeve 117 on the rod 118 in the recess 119 in the post 90. The sleeve 117 is resiliently 105 projected through the medium of a spring 120 (Fig. 5). When the rod 50 is pushed against the small end of the bobbin, the larger end of the bobbin is pushed against the sleeve 117, which sleeve in turn is 110 pushed back to permit the larger end of the bobbin to seat itself on the point 118^a of the rod 118.

By reference to Figs. 4 and 6, it will be observed that prior to engaging the bobbin the cam 33 will hold the dog 65 out of the notch in the bar 50 and hold the roller 64 in elevated position. (See Figs. 4 and 6.) While the dog is so held, the cutter bar will be supported in an elevated position, as shown in Fig. 4, notwithstanding the force of the spring 110 and its block 109 against it. When the cam 34 has rotated out of engagement with the roller on the lever 58, the spring 54 pushes the rod 50 against the bobbin and the latter onto the point 118^a. At the same time that the rod 50 is moving forward, to clamping position, the cutter bar is moving backward out of cutting position. The pusher fingers are held out of pushing 130

position on account of the engagement of the arm 108 with the roller 89. By the time that the bar 50 has moved into bobbin-clamping position, the cam 33 has rotated out of contact with the roller 59 on the lever 57, whereupon the spring 67 places the dog 65 in the notch 66, thus locking the bar 50. The descent of the roller 64 at the same time allows the end of the bar 75 to be lowered, and thus brings the knife (which has previously moved back to a position to begin cutting) into cutting position, but not so that the knife will rest upon the bobbin. The cutter 83, by means of the guard fingers 121, may be so adjusted by screws 86 and 87 (as heretofore explained) as to permit the knife to almost touch the bobbin yet not come in contact therewith so as to score it. At about the time the knife begins its clutching movement the finger 88 engages the rack bar 91, as seen in Fig. 5 to impart a longitudinal movement thereof from left to right. This movement will impart a rotary movement to the pinion 97 in the direction of the arrow in Fig. 5 and impart a rearward movement to the rack bar 99 from the right to the left as seen in Fig. 5, so that any material adhering to the base of the bobbin will be forced by the pusher fingers 107 toward the knife so that it may be severed. In severing the yarn the knife 83 may pass between the pusher fingers 107. Engagement between the finger 88 and the rack 91 imparts only a longitudinal movement to the rack 99, but the spring 106 on the rod 103 will have a tendency to force the end 102 of the rack 189 upward so as to guide the pusher fingers 107 over the surface of the bobbin so as to insure pushing off the lint, yarn and thread which may adhere thereto. As soon as the knife is moved to its full stroke, the crank 35 will begin its retracting movement and the cam 33 will impart a rearward movement to the arm 57 so as to rock the lever 61 and immediately raise the bar 75, withdrawing the dog 65 (which is a part of 61) from contact with the shoulder 66, thus unlocking the rod 50 so that the cam 34 may impart a rearward movement to the lever 58 so as to draw the rod 50 away from the bobbin B, whereby the feed disks 48 and 49 may carry the bobbin which has been cleared onward to be discharged by gravity into a suitable receptacle. The ejector 71 will obviate the tendency of the smaller end of the bobbin to stick in the flared portion 70 of the rod 50. As the rod 50 moves forward the end of the dog 65 will rest upon the forward portion of the bar in front of the notch 66 and the dog will ride thereover. During this time the cutter bar 75 will be supported by the roller 64 until the rod 50 on its return stroke causes the notch 66 to register with the dog 65 in which event the dog will again drop into the notch 66. The

cam 33 will permit the descent of the roller 64 and as a result the cutter bar will be lowered. When the finger 88 begins its rearward movement, it will be raised because the whole bar 75 will be raised on its pivot 77 by the roller 64, thus the roller 89 while engaging the finger 108 will raise the stripper fingers 107 and the spring 92 will project the rack 91 toward the cutter bar so as to impart motion to the pinion 97 in a direction reversed to that indicated by the arrow (Fig. 5) so as to impart a retracting movement to the rack 99 and thus retract the pusher finger, so that all of the parts will be in position to begin a new operation by the time that a new bobbin is positioned or aligned with the rod 50 and the sleeve 117. As soon as the waste yarn has been removed from the bobbin and the bar 50 retracted, the sleeve 117 will push the bobbin off the end of the point 118^a of the rod 118 and the carrier comprising the disks 48 and 49 will move the cleared bobbin along to a point where it may be released by gravity into a suitable receptacle and at the same time present another bobbin to the positioner clamps comprising the rod 50 and sleeve 117.

Immediately below the cutting and clearing mechanism is a suction tube 122 in communication with a suction fan casing (not shown) so that the waste lint and other extraneous matter may be removed and conveyed to a suitable receptacle.

The hopper shown in the drawings is of a limited capacity, but a larger hopper may be employed or the bobbins may be supplied through a conveyer belt in any well known manner.

I claim as my invention:

1. In a bobbin clearer, a cutter, means for causing a relative movement between a bobbin and said cutter and means for withdrawing from the bobbin the yarn severed by said cutter.

2. A mechanism for removing waste yarn from bobbins, comprising a cutter, means for feeding bobbins into position to have yarn thereon severed by the cutter, means for operating said cutter to sever the yarn on said bobbins and means for withdrawing from the bobbins the yarn severed by said cutter.

3. In a bobbin clearer, in combination, a yarn-cutting means; means for moving bobbins to said yarn-cutting means; and means adjacent to said cutting means for carrying off the yarn cut from the bobbins.

4. A mechanism for removing waste yarn from bobbins, comprising a rotary feeding means, a yarn cutter and means for actuating the feeding means to present a bobbin to the cutter.

5. A mechanism for removing waste yarn from bobbins, comprising means for holding a bobbin, means for cutting the waste yarn

by a movement lengthwise the bobbin, and means for withdrawing from the bobbin the yarn severed by the cutting means.

6. A bobbin feeding means, a bobbin positioning means and a yarn cutting means, the path of movement of which is across the path of travel of the feeding means.

7. In a machine for clearing bobbins, a longitudinally movable bobbin clamping means, a longitudinally movable cutter bar and a rotary knife on said cutter bar.

8. In a machine for clearing bobbins, the combination with means for feeding bobbins laterally, means for pushing threads longitudinally of said bobbins, and means for severing said threads.

9. In a machine for clearing bobbins, the combination with a bobbin holder, of a yarn pusher, a cutter, and means for actuating said yarn pusher.

10. In a machine for clearing bobbins, the combination with a bobbin holder, of a yarn pusher, a cutter, and means for imparting a swinging movement to said yarn pusher.

25 11. In a bobbin clearer, in combination, a bobbin support; a cutter-carrying member movable longitudinally of a bobbin and arranged to be supported thereby; and a cutter carried by said member.

30 12. In a bobbin clearer, in combination, a bobbin support; a reciprocatory cutter-carrying member movable longitudinally of a bobbin and arranged to be supported thereby during a portion of its reciprocation; and means for moving said member off the bobbin.

35 13. In a bobbin clearer, in combination, a bobbin support, a reciprocatory cutter bar pivotally and slidably supported at one end and arranged to be supported at its other end upon a bobbin; a cutter on said bar; means for reciprocating said bar; and means for tilting said bar to move the cutter-carrying portion thereof away from the bobbin.

40 14. In a bobbin clearer, in combination, a bobbin support; a reciprocatory cutter bar pivotally and slidably supported at one end; a cutter at the other end of said bar, the last mentioned end of said bar being arranged to be supported by a bobbin; means for driving said cutter comprising a pulley carried by said bar and a belt running over said pulley, means for reciprocating said bar and means for tilting said bar to carry the

55 cutter away from the bobbin.

15. In a bobbin clearer, in combination, a bobbin-clamping means comprising a reciprocatory clamping member; means for feeding bobbins to the clamping means; a pivoted member adapted to lock said reciprocatory clamping member against movement; means for operating said locking member; a reciprocatory cutter bar slidably and pivotally supported at one end, the

60 other end of said bar being arranged to be

supported by the clamping bobbin; a cutter at the last mentioned end of said bar; and means for reciprocating said bar, said locking member being arranged during its unlocking movement to engage said cutter bar and swing the latter away from the bobbin.

70 16. In a bobbin clearer, in combination, bobbin-clamping means comprising a reciprocatory clamping member; means for feeding bobbins to the clamping means; a pivoted member adapted to lock said clamping member against movement; means for operating said locking member; a reciprocatory cutter bar slidably and pivotally supported at one end, the other end of said bar being arranged to be supported by the clamped bobbin; a cutter at the last mentioned end of said bar; and means for reciprocating said bar longitudinally of the bobbin, said locking member being arranged during its unlocking movement to engage said cutter bar near the end of the cutting movement of said bar and raise the latter away from the bobbin.

75 17. In a bobbin clearer, in combination, bobbin-clamping means comprising a stationary clamping member for one end of the bobbin and a reciprocatory clamping member for the opposite end of the bobbin, the last mentioned member being arranged to force the bobbin against the stationary clamping member; and means for operating upon yarn on the clamped bobbin.

80 18. In a bobbin clearer, in combination, two opposite co-acting clamping devices; a rotatory carrier for moving bobbins into alignment with said devices; means for imparting a step-by-step rotation to said carrier; and means for operating said clamping devices.

85 19. A bobbin-clamping mechanism comprising two devices each adapted to engage one end of a bobbin, each of said devices comprising an ejector and means for operating said devices.

90 20. In a bobbin clearer, in combination, a bobbin support; a cutter arranged to travel along a bobbin held in said support; and means for moving yarn on said bobbin into position to be cut by the cutter.

100 21. In a bobbin clearer, in combination, a bobbin support; a member movable longitudinally of a bobbin; a cutter on said member; a pusher member; means for moving said pusher member to push yarn on said bobbin into position to be cut by the cutter; means for moving the cutter-carrying member; and means for moving said cutter-carrying member away from the bobbin, said cutter-carrying member being arranged to remove said pusher member from the bobbin.

115 22. In a bobbin clearer, in combination, a pusher member; a slidably and tiltably mounted member carrying said pusher mem-

- ber; means tending to tilt said member to place said pusher member in engagement with a bobbin; means for moving said pusher member comprising a spring tending to retract said member; and yarn-cutting means arranged to actuate said moving means to advance the pusher member and move it away from the bobbin.
23. In a bobbin clearer, in combination, a 10 slidably mounted rack bar; a pusher finger carried by said rack bar; a second rack bar; a pinion lying between and meshing with both of said rack bars; a spring tending to move the second mentioned rack bar in the 15 direction to retract said pusher finger; and yarn-cutting means arranged to move the second mentioned rack bar in the direction to advance the pusher finger.
24. In a bobbin clearer, in combination, a 20 slidably and tiltably supported rack bar; a pusher finger carried by said rack bar; means tending to tilt said rack bar to place said pusher finger in engagement with a bobbin; a second rack bar; a pinion lying 25 between and meshing with both of said rack bars; means tending to move the second rack bar in the direction to retract the pusher finger; yarn-cutting means arranged to move the second mentioned rack bar in 30 the direction to advance the pusher finger; and means attached to said pusher finger and arranged to be engaged by said cutting means for moving the pusher finger away from the bobbin.
35. 25. In a bobbin clearer, in combination, a yarn-cutting means; and a rotary carrier for moving bobbins to and past said cutting means.
26. In a bobbin clearer, in combination, a 40 yarn-cutting means; a rotatory carrier for moving bobbins to and past said cutting means; and an exhaust air tube adjacent to said cutting means for carrying off the yarn cut from the bobbins.
45. 27. In a bobbin clearer, in combination, relatively stationary bobbin-clamping means; intermittently movable means for carrying bobbins to and past said clamping means; and means for acting upon yarn on a bobbin held in said clamping means.
50. 28. In a bobbin clearer, in combination, relatively stationary bobbin-clamping means; a rotatory carrier for moving bobbins to and past said clamping means; and means for acting upon yarn on a bobbin held in said clamping means.
55. 29. In a bobbin clearer, in combination, relatively stationary bobbin-clamping means; a rotatory carrier for moving bobbins to and past said clamping means; means for giving said carrier a step-by-step rotation; means for actuating said clamping means to clamp a bobbin during the interval between movements of the carrier; and means for acting upon yarn on a bobbin held in said clamping means.
60. 30. In a machine of the kind described, cutting means for cutting transversely through the yarn remnants on bobbins for the removal of said remnants therefrom, combined with power actuating means therefor.
31. In a machine of the kind described, mechanism including a cutter for cutting off the yarn from bobbins, said mechanism including means constructed and arranged to prevent injury to the bobbin from the cutting operation.
32. In a machine of the kind described, the combination with means for cleaning the 80 yarn remnants from bobbins, of a bobbin holder entering axially within a bobbin in holding engagement therewith for holding a bobbin while it is being cleaned, and means for causing relative withdrawing movement 85 between the bobbin and the holder after the bobbin has been cleaned.
33. In a machine of the kind described, a rotary bobbin carrier, and mechanism for cleaning the yarn remnants from the bobbin, 90 including stripping means operating from the small end of the bobbin toward the butt end thereof and operating means for said cleaning mechanism.
34. In a machine of the kind described, a 95 bobbin carrier, a cutter for cutting through the bunch of yarn remnants on the bobbin for its removal therefrom, said carrier including means for holding the bobbin at its opposite ends during the cutting operation. 100
35. In a machine of the kind described, the combination with means for cleaning the yarn remnants from bobbins, of a bobbin holder comprising means operating to roughly position a bobbin when presented thereto, and automatically operated means for accurately centering the bobbin prior to being operated upon by said cleaning means.
36. In a machine of the kind described, means for supporting a bobbin so that its 110 yarn remnant is in exposed position to be removed, combined with a knife, and means to move said knife into severing relation with said yarn remnant.
37. In a machine of the kind described, 115 the combination with means for cleaning the yarn remnants from bobbins, of a bobbin holder comprising means operating to roughly position a bobbin when presented thereto, a centering stud adapted to engage 120 the end of the bobbin, and means for automatically pressing said stud and bobbin lengthwise prior to the operation of said cleaning means.
38. In a machine of the kind described, 125 the combination with means for cleaning the yarn remnants from bobbins, of a bobbin holder comprising a centering stud having a

conical end for automatically centering the adjacent end of the bobbin, and means for forcing said conical end and the bobbin together lengthwise prior to the operation of

5 said cleaning means.

39. In a machine of the kind described, means to hold a bobbin in position to have its yarn remnants cut therefrom, a cutter, and means to move said cutter parallel to

10 said bobbin to cut transversely through the yarn remnants thereof.

40. In a machine of the kind described,

means to hold a bobbin in position to have its yarn remnants cut therefrom, a cutter, means to move said cutter parallel to said bobbin to cut transversely through the yarn remnants thereof, and means for automatically moving said cutter away from the bobbin when not performing the cutting operation.
